VIOLET PHILLIPS, OF NORWICH, ENGLAND.

HEEL OF BOOTS AND SHOES.

Application filed October 14, 1924. Serial No. 743,564.

To all whom it may concern:

Be it known that I, VIOLET PHILLIPS, a British subject, residing at 25 Camberley Road, Norwich, in the county of Norfolk, 5 England, have invented certain new and useful Improvements in Heels of Boots and Shoes, of which the following is a specification.

This invention has reference to improvements in or relating to the heels of boots and shoes, and it consists in an improved method of and means for securing a top-piece or tread-piece on a "Louis" or like wood heel so that not only can such toppiece 10 be very readily detached and replaced by another but the securing means serve to strengthen or reinforce the heel to prevent it breaking across at its narrowest part, as heels of this kind very often do in use.

20 In accordance with my invention two or more holes are bored vertically in the body of the heel, and a vertical groove is formed in the breast of the heel; a rigid metal plate is secured upon the inner face of the top-piece; pins which are adapted to fit slidably in the aforesaid vertical holes are rigidly mounted in the said plate; and the said plate is formed with a lug which projects upwards from its front edge and is adapted 25 to fit in the aforesaid vertical groove. The contour of the said plate may correspond to that of the toppiece, or a smaller plate may be employed. In the latter case the plate may be partially surrounded by a ring 30 of aluminium or other metal of approximately horseshoe shape, or it may be fitted in a shallow recess formed in the inner face of the toppiece so that its face is flush with the said face of the toppiece. The aforesaid pins and lug serve to strengthen the heel besides ensuring stability and accurate fitting of the toppiece on the heel, and the toppiece is firmly secured in position on the heel by inserting a locking pin into a hole 35 formed transversely in the lug and a hole formed in alignment therewith in the body of the heel. If desired, two vertical lugs may be formed on the plate and two grooves in the heel breast, the said grooves being 40 a short distance apart; and a staple may be employed instead of pins as the locking member.

I have illustrated my invention in the accompanying drawing, in which:—

55 Fig. 1 is a plan view of a wood heel ready to receive the detachable toppiece shown

in Figs. 2 and 3 in plan and elevation respectively;

Fig. 4 is a front elevation of the finished heel after the usual leather facing has been 60 applied upon the heel breast; and

Figs. 5 and 6 show respectively, on a larger scale, a locking pin and a tool for extracting same, hereinafter referred to.

Referring to the drawing: A is a wood 65 heel in the body of which holes *a* are bored vertically to receive metal pins *b*, two of which are mounted rigidly in a steel plate C which may correspond in contour to the contour of the toppiece but is shown as T-shaped. The said plate is secured upon the inner face of the toppiece and is formed with a lug *c* by bending upwards at right angles the end portion of the stem of the T; and it is shown as let into an aluminium 70 plate *d* the contour of which corresponds to that of the toppiece. Two of the four pins *b* shown in the drawing pass through the plate *d* into the toppiece B. The lug *c* fits into a vertical groove *e* formed in the breast 75 of the heel, and the toppiece is secured in position upon the heel by engaging a locking pin *f* in a hole formed in the said lug and in a hole *g* formed in alignment therewith in the body of the heel.

As already indicated, a staple may be employed in place of a locking pin, in which event two holes are formed in the lug and corresponding holes, which may diverge or converge, are formed in the heel to receive 80 the legs of the staple.

I may employ a locking pin formed as shown in Fig. 5 with a screw-threaded bore *h*, and provide a simple tool *j*, shown in Fig. 6, for extracting the said pin when it is necessary to remove the toppiece, but an ordinary pin or a screw may be employed, the head of such pin or screw being preferably countersunk in the lug; and, in order to counteract any tendency of the said pin to enlarge the hole in the heel in wear, I may secure a strip of steel *i* in the bottom of the groove *e* in which the lug *c* fits, a hole being bored in the said strip to register with the hole in the lug.

105 What I claim is:—

1. A method of securing a detachable top-piece on a wood heel of the "Louis" type and at the same time reinforcing the heel to prevent it breaking across at its narrowest part, consisting in forming a vertical groove in the breast of the heel and a plurality of vertical 110

holes in the body of the heel, securing upon the inner face of the toppiece a rigid metal plate formed with a lug which projects upwards from the front edge of the plate and 5 is adapted to fit in the aforesaid vertical groove in the heel breast, mounting rigidly in the said metal plate pins adapted to fit slidably in the aforesaid vertical holes in the body of the heel, and inserting a locking pin 10 into a hole formed transversely in the aforesaid lug and a hole formed in alignment therewith in the body of the heel.

2. The combination with a treadpiece for

a wood heel, of a rigid metal plate secured upon the inner face of the treadpiece, a plurality of pins rigidly mounted in the said plate and adapted to fit slidably in vertical holes formed in the body of the heel, and a lug formed on the said plate at its front edge, adapted to fit in a vertical 20 groove in the breast of the heel and in which a transverse hole is formed to register with a hole formed horizontally in the heel to receive a locking pin.

VIOLET PHILLIPS.
